His Attorney.

UNITED STATES PATENT OFFICE.

HENRY E. WARREN, OF ASHLAND, MASSACHUSETTS, ASSIGNOR TO WARREN CLOCK COMPANY, OF ASHLAND, MASSACHUSETTS, A CORPORATION OF MAINE.

MERCURY-TUBE SWITCH.

Application filed September 21, 1923. Serial No. 664,098.

My invention relates to an improved form of mercury tube controller for electric circuits and has for its principal object to provide a mercury tube switch in which 5 there is a quick comparatively long break between mercury contacts when the circuit is opened. Other advantages of my invention will appear as the description proceeds. In my United States Letters Patent No. 10 1,144,973, I have described a mercury tube switch wherein the surface of the tube upon which the mercury moves is roughened to decrease the friction between the mercury and the tube for the purpose of obtaining a 15 more sensitive switch than the ordinary type in which the contacting surface of the tube is smooth. The reasons for this phenomenon are fully explained in the patent referred to above. My present invention 20 utilizes the same phenomenon in combination with other features to obtain an improved type of controller for electric circuits. The features of my invention which I believe to be novel and patentable are 25 pointed out in the claims appended hereto. A preferred embodiment of my invention will now be described in connection with the accompanying drawing in which Figs. 1, 2 and 3 represent different operating positions 30 of a mercury tube switch incorporating my invention and Fig. 4, a cross section of the tube taken on line 4—4 of Fig. 1.

Referring to the drawings in which like parts are designated by like reference characters throughout, I have illustrated a mercury tube switch comprising an inner tube 10 containing a quantity of mercury 11 and an outer tube 12 enclosing the former in the manner indicated, together with suitable 35 electrodes 13 and 14 sealed into the outer tube near the center and one end respectively. The inner tube is made of some refractory material which is not in the least apt to contaminate the mercury under any conditions. I prefer to use for this purpose a 40 glass tube which is free from lead and I find the so-called "pyrex glass" suitable for this purpose. This tube is made either with a hole near its center through which the 45 electrode 13 can enter, or, preferably, with a long narrow slot 10^a extending from one end to facilitate assembling with the electrode 13 in position. One end of tube 10 is flanged inward as illustrated at 15, so as to 50 tend to confine the mass of mercury 11 and also to fit better the corresponding end of the enveloping tube 12. The inner surface of tube 10 is roughened as, for example, by grinding. Chemical action, such as etching, 55 may also be used to roughen the interior of the tube and the degree of roughening may be varied as desirable to obtain different operating characteristics, as will be apparent from the description which follows.

The outer tube 12 may be made of any 60 kind of glass or other suitable material which can be easily manipulated and which will form a perfect seal with the electrodes 13 and 14. Inasmuch as it never comes in contact with the mercury where the arc is 65 broken, this outer envelope 12 need not be free from lead. I find that the ordinary lead soda glass is entirely suitable for this outer tube. A chamber 16 is provided beyond one end of tube 10 in which chamber 70 a portion of the mercury will remain when the tube is in use. The enveloping tube 12 is preferably not roughened on the inside, consequently that portion of the mercury contained in chamber 16 will adhere 75 strongly to the inner surface of tube 12 and when the tube is nearly level, owing to the fact of the adhesion of the mercury in chamber 16 and the non-adhesion of the mercury 80 in the roughened tube 10, and also to the 85 effect of the dam constituted at 19 by the end of the inner tube 10 adjacent the chamber 16, the mercury will break as indicated in Figs. 2 and 3 when the tube is tilted 90 slightly in a counter-clockwise direction in such a manner as to cause the arc to be 95 wholly contained within the tube and this, by the suddenness and very great length of the break, will minimize the generation of heat by the current. The outer and inner tubes are suitably secured in the relation shown as for example by a small spring steel wedge 20 shown in Fig. 4.

It will be understood that the electric circuit controlled by this type of switch is connected in series with electrodes 13 and 14 100 so that when the tube is in the position shown in Fig. 1, the circuit will be closed and when in position shown in Fig. 3, the circuit will be open. It will be noted with this construction that no arcing takes place at the surface of the electrodes, but always between masses of mercury. The electrode should of course be made of some material 105 which will not pollute the mercury. I find 110

platinum is particularly well suited; also steel, although if steel is used, it should be either welded to some other material which can be fused into the glass, or else, alloyed 5 with nickel and covered with copper when the seal is made. The covering of the copper should be removed inside the seal because otherwise, it would mix with the mercury and interfere with its mobility. It is 10 of course necessary that the mercury should be of the greatest purity in this contactor. The interior atmosphere may be of hydrogen or other suitable gas or the air may be exhausted if the current to be broken is low. 15 The operation of the tube is more fully explained as follows: In Fig. 1 the tube has a slight tilt in a clockwise direction so as to close the circuit between the electrodes. This tilt, due to the anti-friction action of 20 the roughened tube with mercury, need not be more than one-half degree from a true horizontal position. The heavy dotted line 17 may be taken as a true horizontal reference line and the lightly dotted line 18 as 25 the axis of the tube. In position Fig. 1, the circuit is closed by the mass of mercury between the electrodes. The tube may contain sufficient mercury to completely fill up the tube between electrodes 13 and 14 when 30 the tube is tilted to a vertical position in a clockwise direction so that the degree of tilt, although it need be very small, is quite immaterial and there is no danger of opening 35 the circuit as is often the case with previous arrangements should the tube be tilted 40 too far in a circuit closing direction. In Fig. 2, the tube is brought back to substantially a true horizontal position so that the mercury flows to the left. The condition 45 of the mercury as shown in Fig. 2 is that which will occur when the tube is being moved from the circuit closing position of Fig. 1 to the open circuit position of Fig. 3. Due to the difference in the adhesion of 50 the mercury on the rough interior surface of tube 10 and the smooth interior surface of chamber 16 and also due to the dam effect at 19, the mercury is drawn out in the form illustrated with a long thin stream in that 55 portion of the tube between the electrodes with a greater amount of mercury surrounding the electrodes themselves. Due to the surface tension of the mercury, this stream will be stretched out, so to speak, until a 60 sudden break will occur at the thinnest point, mercury flowing both ways therefrom at a rapid rate bringing the mercury to the condition shown in Fig. 3 which illustrates the tube at the end of the open circuiting movement. Not only does this provide a 65 quick break and a long arcing space, but the arc is entirely between mercury contacts, consequently no burning and wearing away of the electrodes will ever occur and the mercury will not become contaminated by chemi-

cal action which might otherwise be produced if the arc was allowed to play on the electrode. Furthermore, the resistance of mercury being somewhat like six times that of copper, the drawing out of the mercury 70 into a long, thin stream just before the circuit is opened, acts to some extent as an adjustable resistance in decreasing the current strength. By suitably proportioning the dimensions of the tube a considerable current at a considerable voltage may be controlled by this simple circuit breaker. The action of the tubes can be modified by modifying the dimensions and degree of roughness of the tube and certain portions may 75 be roughened more than others. The switch is very sensitive, requiring not more than one degree of change in position between its open circuit and closed circuit position whereas the ordinary mercury tube 80 switch requires from ten to twenty degrees tilt between these positions. The tilt illustrated in the drawings is exaggerated for the sake of clearness and is more than is necessary although any greater amount of tilt in 85 either direction is permissible and will not affect the conditions of the circuit. Due to the fact that a mass of mercury tends to 90 cling together due to surface tension, a much larger stream of mercury will be available between the electrodes at the instant the circuit is closed than when it is open, consequently, the circuit is quickly and positively closed when the tube is tilted to a circuit 95 closing position. 100

Although I have shown but a single modification of my invention, it will be evident to those skilled in the art that various changes may be made therein; for example, both ends of the tube shown might be made like the right hand end to provide a double throw, a single pole circuit breaker. I do not consider the dam 19 essential but preferable to obtain the best results. 105

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means. 110

What I claim as new and desire to secure by Letters Patent of the United States, is: 120
 1. An electric circuit controller comprising a tubular sealed chamber of insulating material, a pair of electrodes sealed into said chamber, so as to provide considerable arcing space between said electrodes, the interior surface of the chamber closely adjacent one electrode being smooth and the interior surface between the electrodes being roughened and a conducting fluid such as mercury contained within said chamber in 125 130

sufficient quantity to electrically connect said electrodes when the chamber is in one position, the circuit controller being constructed so that the circuit therein is broken by the separation of the mercury over the roughened surface of said chamber when tilted toward the open position.

2. A mercury tube circuit controller comprising a sealed tubular chamber of insulating material, two electrodes sealed into said chamber, so as to provide considerable arcing space between said electrodes lengthwise of the chamber, the interior of the chamber between the electrodes being roughened and the interior of the chamber closely adjacent one electrode being smooth, a low dam between said electrodes, and sufficient mercury in said chamber to cover said dam and connect said electrodes when the tube is in one position, the circuit controller being constructed so that the circuit therein is broken by the separation of the mercury over the roughened surface of said chamber when tilted toward the open position.

3. An electric circuit controller comprising a sealed glass cylindrical chamber, having an enlarged portion at one end, said enlarged portion having a smooth interior surface and substantially the remainder of the interior of said chamber being roughened, an electrode sealed into the enlarged portion of said chamber, an electrode sealed into said chamber intermediate its ends so as to provide a considerable arcing space between said electrodes and a fluid conductor such as mercury contained within said chamber of sufficient quantity to connect said electrodes when the chamber is in one position, the circuit controller being constructed so that the circuit therein is broken by the separation of the mercury over the roughened surface of said chamber when tilted toward the open position.

4. A mercury tube circuit controller comprising a sealed glass tube, the interior surface of which is smooth, a glass tube having a roughened interior surface inserted in said sealed tube so as to leave a space at one end, an electrode sealed into said outer tube and communicating with the bore of the inner tube near its center, and sufficient mercury contained within said tubes to connect the electrodes when the tube is in one position.

5. A mercury tube circuit controller comprising a pair of concentrically fitted glass tubes, the outer one of which has a smooth bore and is sealed, and the inner one of which has a roughened bore and has an open end spaced away from a sealed end of the outer tube so as to leave an enlarged chamber thereat, an electrode sealed into said chamber through the outer tube, an electrode sealed into the outer tube near its center and communicating with the bore of the inner tube, and mercury contained within said tubes of sufficient quantity to connect said electrodes when the tube is in a horizontal position.

6. A mercury tube switch comprising a cylindrical chamber of refractory material, a pair of axially spaced electrodes in said chamber, mercury contained within said chamber in sufficient quantity to electrically connect said electrodes in one position of the chamber, the interior surface of the chamber having a varying degree of roughness whereby the true level of the mercury in said chamber is modified in a manner so as to cause the mercury to be drawn out into a stream of varying cross section between said electrodes when the tube is tilted toward an open circuit position.

In witness whereof, I have hereunto set my hand this 13th day of Sept., 1923.

HENRY E. WARREN.
